SASH BALANCE CASING

Owen L. Dautrick, Detroit, Mich.

Application January 12, 1938, Serial No. 184,515

6 Claims. (Cl. 20—52)

The present invention relates in general to means for balancing window sashes and other analogous articles which require to be raised and lowered, and is more particularly concerned with improvements in devices for such purpose of the type wherein the weight of the article is balanced by the action of one or more springs.

It is a primary object of the present invention to provide an improved sash balance of the spring type, which may be used with standard window frames.

A further object is to provide novel enclosing means for concealing a sash balance mechanism of the herein described type, which effectively conceals the device yet enables ready and easy access thereto when necessary. Another object is to provide in a device of the character described, improved means for connecting the balancing springs with the associated instrumentalities, whereby improved spring action and operation may be secured.

A still further object is to provide improved means in connection with window jambs, whereby pressure may be residually applied against the sash stiles to frictionally resist movement of the sashes from normal or adjusted position, and prevent canting or lateral tilting of sashes particularly where the sashes are counterbalanced at one side only.

It is also an object to provide improved means for adjusting the spring tension to accommodate the mechanism for window sashes of different weights.

Although for purposes of illustration the invention is disclosed as being utilized with window sashes, it will be apparent to those skilled in the art that the invention may with equal facility be utilized with other types of closure panels, such as doors, sliding panels, etc., without departing from the principles of the invention.

Other objects and features of the invention will more fully appear from the following detailed description, taken in connection with the accompanying drawings, which illustrate a single embodiment thereof, and in which:

Figure 1 is an elevational view of a window frame or casing with window sashes therein and having my improved balance mechanism applied thereto;

Figure 2 is an enlarged fragmentary vertical sectional view through the same, taken substantially on line II—II of Fig. 1;

Figure 3 is an enlarged transverse fragmentary sectional view through the compartment of

the casing housing the sash balance mechanism, taken substantially on line III—III of Fig. 2;

Figure 4 is an enlarged fragmentary sectional view of the same, taken substantially on line IV—IV of Fig. 2;

Figure 5 is an enlarged vertical fragmentary section at the end of the sash balance compartment to show the details of the end supporting bracket, taken substantially on line V—V of Fig. 4;

Figure 6 is a similar view at the opposite end of the sash balance compartment, taken substantially on line VI—VI of Fig. 3;

Figure 7 is a fragmentary sectional view taken through one of the window jambs to show the details of the weather strip and the manner in which it is secured to the jamb, taken substantially on line VII—VII of Fig. 1;

Figure 8 is an enlarged fragmentary intermediate section through the sash balance compartment, taken substantially on line VIII—VIII of Fig. 3;

Figure 9 is an enlarged fragmentary view partly in section, showing details of construction of the spring rod and tape winding drum associated therewith; and

Figure 10 is a fragmentary detail view partly in section showing the manner in which the tensioning springs are secured to the spring rod.

As shown on the drawings:

As illustrative of the invention, the invention is disclosed as being applied to a window frame or casing generally indicated at 11, in which upper and lower sashes 12 and 13 are mounted for raising and lowering movement in the usual manner.

More specifically, the window frame or casing embodies spaced side jambs 14 and 15 which are interconnected on their uppermost ends by a fixed head member 16.

The uppermost ends on the side jambs cooperate with the head member to form the ends and top of a box-like compartment 17 at the top of the casing for receiving the sash balancing mechanism which will hereinafter be described in detail. The compartment is closed on its rear side by a transversely extending back member 18, and on its forward side by means of a face member 19.

As shown in Figs. 2, 5 and 6, it will be observed that the face member 19 is arranged to provide a plaster ground for a plaster coat shown at 20. The forward surface of member 19 is roughened in any suitable manner so as to enable the plaster, when placed thereon, to grip the surface. For this purpose, it is found that spaced

longitudinally extending grooves as shown at 21 will work very satisfactorily.

It will be noted that the use of this type of plaster ground, and since jamb compartments are eliminated with my improved spring balance mechanism, it is possible to use a narrow casing instead of the extremely wide casings formerly used.

The sash balancing mechanism for each sash 10 may be of either the single or double type. In the single type, the sash is connected at one side only to the balancing mechanism. In some cases, the single arrangement is preferable as it makes a more economical installation. However, my 15 improved balancing mechanism may with equal facility be incorporated into the double arrangement, wherein a connection between the mechanism and the sash is made at both sides of the sash.

20 In the invention as disclosed on the drawings, both the single and double balance mechanisms are disclosed, a single balance being utilized in connection with the upper sash, and a double balance being utilized in connection with the lower sash.

25 As shown, the double balance arrangement comprises an elongate rod 22 which is provided at its ends with metallic end caps 23 which are centrally apertured to receive one end of a trunnion pin 24 which is driven through the opening of the cap into the end of the rod 22 and projects outwardly from the cap end to form a pivot for a winding drum 25 which may be constructed of wood material.

30 The rod 22 is removably supported for rotation in end brackets 26 and 27 which are secured as by screws 28 in surface engagement with the respective side jambs 14 and 15.

35 Each bracket is provided with a centrally cut 40 out portion 29 which admits of the associated trunnion pin being seated behind a hooked projection 30 by carrying it through an entrance opening 31. In its supported position in an associated end bracket, the pin 24 projects outwardly past the bracket into a dado or groove 32 at the upper end of the associated jamb.

40 For additionally supporting the rod 22 intermediate its ends, an intermediate bracket 33 is provided, which may be secured to the fixed head 50 member by means of a suitable screw 34.

45 The rod 22 extends through a suitable aperture 35 in the bracket, as shown in Fig. 8. The rod is rotatably supported in the bracket in an open ended sleeve 36 which partially surrounds the rod and has one end thereof outwardly deflected to form a radially extending end flange 37. The other end of the sleeve is inwardly deflected to form a radially extending end flange 38 which is adapted to fit into a groove 39 extending longitudinally of the rod in its surface. This sleeve 55 may be supported against endwise movement in the bracket in any suitable manner.

60 Respectively disposed on opposite sides of the intermediate bracket, tension springs 40 and 41 are coiled around the rod. One of these will be a right hand spring and the other a left hand spring. The springs are similarly connected at their ends with the winding drums and the rod 22.

65 70 As shown, for example, in Figs. 9 and 10, the outermost end of the spring 41 is anchored to a sleeve 42 which surrounds the innermost end of the winding drum 25 and is secured thereto as by a pin 43 for unitary movement with the drum.

75 Any appropriate means may be utilized for se-

curing the spring end to the drum, but one satisfactory method is to provide the sleeve 42 with a projection 44 over which the spring end may be hooked. If desired, the projection may be bent around the spring to hold it against the end of the winding drum.

10 The other end of the spring is secured to a sleeve 45 which surrounds the rod 22. This sleeve is retained against rotational movement relative to the rod by means of an internal longitudinally extending rib 46 which is adapted to extend into the groove 39. It will thus be evident that the sleeve as thus secured will be rotated with the shaft, but is free to move longitudinally of the rod when the associated spring is tensioned.

15 The winding drums 25 are preferably grooved as shown at 47 to facilitate the winding thereon of a flexible tape 48 which is connected at its one end to the winding drum and at its other to one of the sash stiles.

20 The end of the tape, which is connected to the sash stile, is secured in a novel manner, as shown in Fig. 6. The lowermost end of the tape is deflected as shown at 49. The deflected end of the 25 tape is inserted into a saw cut 50 which is taken across the face of the stile at the point where it is desired to connect the tape. The deflected end is laterally retained against removal from the saw cut by means of the associated jamb. Moreover, the deflected end 49 is held against endwise movement from the saw cut by means of the parting stop 51 which is disposed between the sashes. It will be noted that the upwardly extending portion of the flexible strip lays along the associated 35 sash and is disposed between the sash and the parting stop.

25 For simultaneously tensioning the springs 40 and 41 to the same amount, a tensioning pulley 52 is loosely mounted on the rod 22 for rotative 30 movement thereon. This pulley has a depressed surface upon which a winding cord 53 may be wound. One end of the pulley is provided with clutching teeth 54 which are adapted, when the pulley is slid along the rod into abutting relation with the sleeve 36, to clutchingly engage the flange 37. Upon rotation of the pulley 52 by pulling upon the tensioning cord 53, the rod 22 will be rotated in the proper direction to tension the springs 40 and 41. These springs may be tensioned just the right amount to counterbalance the weight of the sash which is connected thereto through the tape 48. Rotation of the rod in the opposite direction, which would tend to release the tension on the springs, is prevented by means of a suitable latching pawl 55 which is swingably mounted on a pivot 56 secured to the intermediate bracket 33. This pawl is held in latching position by gravity. Should it be desirable at any time to lessen the tension of the 40 springs, this may be easily accomplished by actuating the tensioning pulley in a tensioning direction sufficiently to enable the pawl to be manually released, whereupon by releasing the pressure on the tensioning cord 53, will permit the springs to unwind and rotate the shaft until the proper tension remains in the springs, whereupon the pawl may be released to again restrain unwinding movement of the rod.

45 Referring to Fig. 3, it will be noted that the 50 single balance arrangement operates on the same principle as the double arrangement, except that instead of providing two springs and two winding drums, only one spring and one winding drum is provided. In the single arrangement, instead 55

of having connecting tapes secured at opposite sides on the sash, the single tape is secured at one side of the sash. It will also be noted that in the case of the single arrangement, the tensioning pulley may be removed from the rod when it is not being used.

By utilizing a spliced connection between the end of the spring associated with the rod and the rod, the torsional effect only of the spring is utilized. Moreover, such a connection prevents the spring coils from overlapping and locking with each other when tensioned and the spring coils will at all times lay smoothly and regularly along the rod. This arrangement also permits the use of different lengths of springs without having to modify the other parts of the mechanism.

A novel closure for the compartment containing the sash balance mechanism is provided. This closure which is generally indicated at 51 forms a removable sub-head which admits of easy access to the balance mechanism compartment whenever desired.

This closure consists of right and left end blocks 53 and 59 which are adapted to fit into suitable dados or grooves 60 extending horizontally of the top ends of the respective side jambs.

The end blocks are respectively provided with suitable cut-outs as shown at 61 and 62 in Fig. 6, these cut-outs or notches extending to the inserted end edge of the block so as to enable the blocks to be moved endwise into the associated dado or groove 60 with the tapes 48 passing therethrough.

The forward face of the back plate 48 is provided at its lower edge margin with a longitudinally extending groove 63 which is adapted to receive a tongue 64 formed on the rear edge of each of the end blocks and supporting the block in horizontal position, when it is moved into the associated groove 60. In its normal position, the end block extends over the uppermost end of the parting strip along the side of the associated jamb.

The end blocks may be easily inserted in normal position or removed as desired. In order to prevent removal of these blocks, there is provided an intermediate section 65 which is likewise provided at its rear edge with a tongue 66 adapted to fit into the groove 63. In order to enable this section to be swung into position by pivoting the same about the tongue 66 in the groove 63, the upper corner of the tongue is slightly rounded as shown at 67. Also in order to permit the forward edge of this section to swing past the lower edge of facing member 19, the forward edge of the section should be rearwardly beveled as shown at 68.

The ends of section 65 are arranged to abut the ends of the end blocks and form rabbet joints as shown at 69 and 70, in Fig. 4. The section 65 may be secured at its ends to the respective end blocks by means of suitable screws 71 at the joints, the heads of these screws being accessible from the outside of the compartment for the balance mechanism. It will be evident that with the intermediate section 65 thus secured in place, a removable sub-head is formed which is securely held against endwise movement as well as vertical movement, but which may be readily moved at any time it should be so desired.

As shown in Fig. 8, the parting stop at the

sub-head or closure means, may be supported on the intermediate section 65.

In any spring balanced mechanism where the load is constant and the power supplied by the spring is variable, some means are necessary to balance the sash at all points of its position of adjustment.

For this purpose, the present invention contemplates the utilization of novel weatherstripping as shown at 72 in Fig. 7. This weatherstrip is secured to the side jambs and forms a resilient lining against which the window sashes are adapted to bear. In partially compressed positions, the window stripping exerts a constant pressure against the sash stiles. This pressure not only prevents rattling of the sashes, dust seepage therearound, wind and weather leakage, but, also further enables expansion and contraction of the sash and frame. Moreover, since the weatherstripping covers the width of the side jamb, the possibility of window sticking from paint is greatly reduced and enables movement of the window for the purpose of breaking paint locks after the same has been painted.

The weatherstripping also is of special advantage when used in connection with the single spring arrangement of balance mechanism, wherein the mechanism is connected to one side of a sash. The resilient window strip prevents canting or cocking of the sash in the frame and enables this type of balance mechanism to be used with wider windows than would otherwise be possible.

As more specifically shown in Fig. 7, the window strip is provided along its center line with a longitudinally extending groove which is adapted to fit into the groove ordinarily used for receiving the supported edge of the parting stop associated with a side jamb. This groove is indicated at 73. From this groove the marginal edges of the strip extend outwardly in any desired curve so that they may resiliently engage the respective sashes of the window during raising and lowering movements.

While a window strip of one piece construction is adapted to extend over the side jamb both forwardly and rearwardly of the parting stop, it is apparent that the forwardly extending and rearwardly extending portions may be formed as separate strips.

The novel feature of my weatherstrip arrangement is that the weatherstrip is solely supported in position by the securing means for the parting stops. In the use of the improved strip, it is not necessary to provide additional fastening means.

From the foregoing description, it will be evident that the present invention provides an improved sash balance mechanism of the spring type which may be utilized with standard window frames; which embodies novel enclosing means for the balance mechanism, whereby the mechanism is effectively concealed and yet is so arranged that access to the mechanism may be readily and easily accomplished, when necessary; improved means for connecting the balancing springs with the associated parts of the mechanism, whereby novel and improved spring action may be secured; which utilizes novel means for applying frictional pressure against the sash stiles to maintain the sashes in adjusted position, and prevent canting or lateral tilting of the sashes particularly when the sashes are connected to the balancing mecha-

nism at only one side; and which provides improved means for adjusting the spring tension to accommodate the balance mechanism for window sashes of different weight.

5 It is of course to be understood that although I have described in detail the preferred embodiment of my invention, the invention is not to be thus limited but only insofar as defined by the scope and spirit of the appended claims.

10 I claim as my invention:

1. The combination with a window casing having a box-like compartment at its top; of a spring balance mechanism disposed in said compartment, a bottom closure for said compartment, and an elongate flexible member operatively connected to said mechanism and passing thru an opening in said closure, said closure having a section removable independently of the portion of said closure containing said opening.

15 2. The combination of a window casing having a box-like compartment at its top, a bottom closure for said compartment, a spring balance mechanism in said compartment, and an elongate flexible member having one end operatively connected with said mechanism and passing thru said closure to the exterior of the compartment, said closure comprising a plurality of connectable and disconnectable sections.

20 3. The combination of a window casing having a box-like compartment at its top, a bottom closure for said compartment, a spring balance mechanism in said compartment, and an elongate flexible member having one end operatively connected with said mechanism and passing thru said closure to the exterior of said compartment, said closure comprising a pair of end sections connected by a removable intermediate section, said end sections being removably supported from the casing and normally retained against removal by the intermediate section.

25 4. The combination of a casing having a box-like compartment at its top, a spring mechanism in said compartment, a flexible strip connected at one end with said mechanism and passing to the exterior of said compartment, and a sectionalized

bottom closure for said compartment comprising a pair of end sections removably supported on said casing, and an intermediate section removably connectable at its ends to the end sections and acting to retain the end sections against removal, and a cut out portion in one of the end sections for the passage of said flexible strip.

30 5. In combination, a casing having a box-like compartment at its top, a horizontal groove in each end wall of the compartment at its bottom, removable bottom closure means for said compartment, said means comprising a pair of end sections and an intermediate section, each end section being movable endwise into a position with one edge disposed in one of said grooves, means for removably securing the intermediate section with its ends in abutting relation with the end sections, whereby the end sections are retained against movement from their associated grooves and the closure means as a whole is supported against vertical movements, spring means in said compartment, and an elongate flexible member connected at one end to said spring means and passing to the exterior of said compartment thru a slot in one of said end sections.

35 6. In combination, a casing having a box-like compartment at its top, a horizontal groove in each end wall of the compartment at its bottom, removable bottom closure means for said compartment, said means comprising a pair of end sections and an intermediate section, each end section being movable endwise into a position with one edge disposed in one of said grooves, means for removably securing the intermediate section with its ends in abutting relation with the end sections, whereby the end sections are retained against movement from their associated grooves and the closure means as a whole is supported against vertical movements, spring means in said compartment, and elongate flexible members connected with said spring means and passing to the exterior of said compartment thru cutouts in said end sections.

40 OWEN L. DAUTRICK. 45
